TELEPHONE SYSTEM

Thomas F. Crocker, Chicago, Ill., assignor to
Associated Electric Laboratories, Inc., Chicago,
Ill., a corporation of Delaware

Application November 30, 1934, Serial No. 755,263

21 Claims. (Cl. 179—27)

The present invention relates to telephone systems in general, but is concerned more particularly with telephone systems in which connections are set up through the medium of automatic switches.

The main object of the invention may be stated to be the provision of suitable apparatus and circuit arrangements for use at a toll board in an automatic exchange whereby the automatic switching apparatus associated with the toll board is more economical and, at the same time, is more flexible in operation.

General description

15 The system disclosed herein may be considered as an improvement on the automatic toll switchboard disclosed in the Crocker and Tharp Patent No. 1,883,589, granted October 18, 1932. In the Crocker and Tharp patent, the several sections of the toll switchboard were each specialized for the handling of a given type of traffic, such as (1) traffic incoming over toll lines; (2) traffic originating at the local automatic exchange and destined to be trunked over toll lines leading to other exchanges; and (3) the handling of delayed calls, wherein the operator sets up a connection from her position to each of the lines involved, known as a tail-to-tail connection.

20 A feature of the switchboard disclosed herein is that an operator at any position of the switchboard may complete any one of the three classes of connections above mentioned. Each position, therefore, is a combination position. In order to enable this to be accomplished in a practical manner, and in order to simplify and reduce the overall cost of the switching equipment, each toll operator's position is provided with a group of finder-selector links, each equipped with a finder which may be referred to as an answering switch, and a selector which may be referred to as a calling switch. To complete any call through her position, the operator causes or permits the answering switch to make connection with the calling circuit and she causes the calling switch 25 to make connection with a desired called circuit.

25 Since an operator must be able to complete a connection between a toll line in one group and a toll line in another group, all of the toll lines are accessible both to the answering switch and to the calling switch of each finder-selector link. The one-way trunk lines incoming to the switchboard from the local automatic switches of the exchange, however, are accessible to only the answering switches, as they are used for originating calls only. Similarly, the toll-service trunk

lines, over which calls are completed by way of automatic switching equipment to the local subscribers of the exchange, are one-way trunk lines and they are accessible to the calling switches only.

30 In order to enable the operator to direct the operation of the hunting-type answering and calling switches of a link which she may be using, each operator's position is provided with a so-called by-pass selector, and this selector has access to all of the toll lines and is provided with circuit arrangements controlled from the operator's position equipment so that she can make connection with any toll line through the by-pass selector and cause either the calling switch or 35 the answering switch of a link circuit in use to find and connect with the same toll line. A feature of this arrangement is that the operator may cooperate with the distant toll operator to change an established connection from one toll line to another toll line of the same group whenever it appears that the toll line being used is defective. She does this by causing the by-pass selector to make connection with another toll line in the group being used, after which she causes 40 her answering switch or her calling switch, as the case may be, to be reoperated to find the new toll line.

45 An additional feature of improvement over the arrangement in the above-mentioned patent is that the operator may selectively release the two ends of a connection. This is of utility particularly in a connection involving a toll line and a local subscriber's line. The connection to the local subscriber's line may be released immediately, while the connection to the toll line is maintained until the operator has given ring-off supervision over the toll line to the distant operator and has secured the proper response.

50 A feature of the disclosure is that the operator may cause the calling switch to hunt for and connect with any idle toll-service trunk line (to be used in setting up a connection to a local automatic line) the by-pass selector not being used for this operation.

55 A further feature of the arrangement is that each position is provided with a group of identity lamps, controlled according to the attained position of the answering switch, to enable the operator to identify the calling group of lines to which the link is connected through the medium of the answering switch. Moreover, the arrangement permits an individual identity lamp to be provided for each line in any desired group so that the operator may know also with which

line the answering switch is in connection, as well as the group to which the line belongs. This latter arrangement is of especial utility in enabling an operator to make a repair record when a toll line is found to be defective when a connection has been set up thereover.

Another feature of the present disclosure is that the toll operator may ring back over a connection set up to her switchboard from a 10 subscriber of the local exchange and resignal such subscriber in case he replaces his receiver prematurely, a suitable by-passing arrangement being provided for by-passing the ringing current around the repeating coil windings associated with the trunk circuit involved.

Other objects and features of the invention, for the most part incidental to those set forth above will be understood best upon a further perusal of the description.

20 Description of drawings

Referring now to the accompanying drawings, comprising Figs. 1 to 7, they show a sufficient amount of the apparatus involved in a system embodying the features of the invention to enable the invention to be understood. In order for the drawings to be understood best, the sheets on which Figs. 1, 3, and 4 are drawn should be arranged in order, and the sheets on which Figs. 30 5 and 6 are drawn should be placed in order, with Fig. 5, part 1, directly below Fig. 3.

Fig. 1 shows the toll line circuit TLC, individual to the toll line TL and accessible to the answering switch AS, Fig. 3, by way of conductors 107 to 110.

35 Fig. 2 shows the long distance circuit LD incoming from banks of the local selectors and accessible to the answering switch AS, Fig. 3, by way of conductors 207—210. The circuit LD is sometimes referred to as a C. L. R. (combined line and recording) circuit.

40 Fig. 3 shows the link circuit L1, provided with an answering switch AS and a calling circuit CS. This link circuit may be compared to a cord circuit in a manual switchboard with the wipers 311—315 corresponding to the calling plug and the wipers 321—325 corresponding to the answering plug of the cord.

45 Fig. 4 shows the toll service circuit TSC, which extends from the bank of the calling switch CS to a toll service selector (not shown) through which connections may be set up to the lines of the local automatic subscribers.

50 Fig. 5 shows the position equipment common to a number of links such as L1, and including the operator's headset and keys, together with the associated controlling relays.

55 Fig. 6 shows the by-pass selector EPS having access to all of the toll lines which may be served through the switchboard. This by-pass selector may be considered as position equipment in that only one is provided at an operator's position.

60 Fig. 7 shows a local circuit LC for use in place of the circuit TSC, Fig. 4, in the event that the switchboard disclosed herein is used in an exchange not having a toll-service trunking system, but making use of the regular local automatic switches for the setting up of connections from the toll switchboard to desired automatic lines.

70 Position arrangement

75 It is assumed, for convenience of description, that the switchboard disclosed is a two-position switchboard, of which the position equipment disclosed in Figs. 5 and 6 is located at the first position. The similar equipment at the second

position is not shown, with the exception of the transfer key K18, Fig. 5, interconnected with the transfer key K17 of position 1 for the purpose of enabling either operator to use her own headset equipment when she is handling calls from both 5 positions, in times of light traffic.

The cables C1, C2 and C3, at the first position contain the indicated conductors for making the necessary multiple connections between the common position equipment and the various 10 link circuit, such as the link circuit L1, Fig. 3. It will be understood, of course, that a sufficient number of these link circuits is provided to handle the estimated traffic requirements.

The second position also is provided with a 15 group of link circuits, each similar to the link circuit L1, Fig. 3, and with equipment such as the equipment disclosed in Figs. 5 and 6, common to the group of link circuits.

20 Link switches

The answering switch AS is a rotary switch of a familiar type, and each of its wipers 311 to 315 may have, for example, fifty contacts in the associated bank, of which only six are shown. 25 The self-interrupting driving magnet 310 is arranged to drive the wipers step-by-step over the contact bank, the wipers preferably being advanced upon the restoring stroke of the magnet. The calling switch CS is similarly constructed, and it includes the wipers 321 and 325 and the driving magnet 320.

Trunk connections

Considering now the connection of trunk lines to the banks of the answering and calling switches, it is to be noted that the first set of indicated contacts in the bank of the answering switch AS is connected through conductors 207—210 with the long-distance or toll-recording circuit LD. It is assumed that the second indicated contact set in the answering-switch bank is also connected to a similar long distance trunk.

The third and fourth indicated contact sets in the answering-switch bank are allotted to the group of toll lines of which toll line TL is one. 45 The second toll line of the group is not shown. It is assumed that the toll line TL extends to a distant automatic exchange, equipped with a similar automatic toll board.

The fifth and sixth indicated contact sets in 50 the bank of the answering switch are allotted to another group of toll lines (not shown) assumed to extend to a distant manual exchange and having, therefore, a manual toll switchboard.

Considering now the bank of the calling switch 55 CS, the showing of this bank also has been abbreviated so that only six of an assumed fifty contact sets are indicated.

Contact sets 1 and 2 in the banks of the calling switch, instead of being assigned to long-distance, 60 or toll-recording, trunks, are assigned to trunk lines leading to the toll-service switching system, through which calls are completed to desired local lines. The first set of indicated contacts is connected by way of conductors 371—374 to the toll 65 service circuit TSC, Fig. 4. The second indicated contact set is assumed to be similarly connected to another toll-service circuit.

The third set of indicated contacts in the calling switch CS is assigned to the same toll trunk 70 line associated with the third indicated set of contacts in the bank of the answering switch AS, the contacts being connected with the toll line circuit ILC through the medium of conductors 75

361, 362, and 363, of the group of conductors 361—365 and 365' assigned to serve as the called multiple of the toll line TL. The remaining indicated contacts in the bank of the calling switch CS are assumed to be similarly connected to the called-multiple conductors of the remaining toll lines which appear as calling lines in the bank of the answering switch AS.

Inter-position multiplying

It is to be understood that the banks of the several answering switches at the same position are multiplied together by the usual bank multiple and that a similar, but separate, multiple exists as regards the banks of the calling switches such as CS. As regards the relationship of the banks of the answering and calling switches of one position with the banks of the similar switches of the other position, certain of the bank-multiple conductors are common to both positions and others are not. For example, the contacts in the banks of the identity wipers such as 313, Fig. 3, are not multiplied between positions, as a group of identity lamps such as 331—334 is provided for the other position and interference between the two positions as regards the lighting of the lamps is not desired. In addition, the second to sixth indicated contacts in the bank of the combination supervisory and marking wipers such as 314 are not multiplied between positions, as the marking conductors, such as 109, must be maintained local to one position.

However, all the contacts in the banks of the wipers such as 311, 312, and 313, as well as the first and second indicated contacts in bank of wiper 314 are multiplied between positions, so that the corresponding conductors are accessible in common from both positions. The reason for the severance of the multiple and the duplication of conductors as regards the two positions will become more apparent as the description progresses.

It is to be noted that conductors such as 207 and 107, etc., are each provided with a short arrow-headed connection extending diagonally upwards. This symbol has been chosen to indicate that the conductor to which it is applied is multiplied into both positions.

At the calling switch CS, it is to be noted that the bank multiple extends through both positions except as regards the banks of the marking wipers, such as the marking wiper 323, which is a separate multiple for each position. It is to be noted that the ones of the conductors shown in association with the calling switch CS which are common to both positions are each provided with the above-mentioned short arrow-headed symbol pointing diagonally upward.

Link equipment

In addition to the answering and calling switches AS and CS, the link L1 is provided with answering- and calling-cut-through relays 301 and 304, ring-up relay 302, and the link-connect relay 303, which may be operated to connect the link with the associated position equipment of Figs. 5 and 6. In addition, the link is provided with a combined talking and monitoring key K1. The remaining equipment which is necessary to the successful operation of the link in the setting up and releasing of connections is to be found in Figs. 5 and 6.

Position equipment

The equipment disclosed in Fig. 5 includes the operator's head-set, containing the usual trans-

mitter and receiver and having associated therewith the repeating coils or induction coils 531 and 532. The relays 501—519 are provided to control the various operations in a manner to be explained; the keys K4—K8 are associated with the answering end of the links, such as the link L1; and the keys K11 to K16 are associated with the calling end of the link circuits, such as L1.

The by-pass selector

The by-pass selector BPS, Fig. 6, is a ten-level Strowger switch of the familiar up-and-around type, being provided with vertical, rotary, and release magnets 615, 616, and 617. The switch has off-normal contacts 611 and 612, operated when the switch is moved from its normal position; individual-level shaft contact 613, assumed to be adjusted to be closed whenever the wiper of the switch is opposite the second level of its bank; and overflow contacts 614, which are caused to operate whenever the wipers 631—635 are rotated off the last (tenth) set of bank contacts in a level.

Detailed description

The disclosure having been described generally, a detailed description of the operation of the apparatus disclosed will now be given. For this purpose a description will first be given of the operations involved in setting up a call outgoing from the exchange in which the automatic toll switchboard is located.

An outgoing call

For the purpose of describing the operations involved in completing an outgoing call, it will be assumed now that a subscriber, desiring to converse with a subscriber in a distant exchange, has operated an automatic selector to make connection with a toll-recording or long-distance trunk such as the one associated with the equipment LD, Fig. 2. Connection to the long-distance trunk is made by way of conductors 221, 222, and 223 in the well known manner.

Seizing circuit LD; grounding start conductor 212

Upon the connection being made, line relay 202 energizes over conductors 221 and 223 by way of the left-hand windings of repeating coil 206 and contacts of the ringing relay 201. Upon energizing, relay 202 closes a circuit for release relay 203 at its inner armature, while at its lower armature it connects the lower talking conductor through contacts of the cut-off relay 204 and the associated small-capacity ring-back condenser to the common intermittent generator lead 211. This connection enables the subscriber to hear an intermittent ringing tone to inform him that the connection has been extended to the toll switchboard.

When release relay 203 energizes, under the control of line relay 202, it marks conductor 208 in the banks of the answering switches in both positions by connecting it to the ungrounded, negative pole of the exchange battery by way of cut-off relay B3 and the associated resistor 205 in parallel; it places ground potential on the release-trunk conductor 322 at its inner lower armature so as to maintain the long-distance trunk guarded and to maintain the connection established to the trunk; and at its lower armature it places ground potential on start conductor 212, which is common to all of the circuits such as LD and all of the circuits such as TLC.

10

25

45

60

65

75

Conductor 212 is, moreover, common to both sets of position equipment, as indicated by the short arrow-headed line extending diagonally upward from conductor 212 in Fig. 3. Therefore, 5 the grounding of start conductor 212 causes a response in both positions.

In the first position, the grounding of conductor 212 closes a circuit through contacts of cut-off relay 516 for start relay 507. Start relay 507 thereupon operates and closes a circuit for the answering pilot light 523 so as to give the operator visual indication of the call. Start relay 507 also closes a circuit at its inner upper armature for the upper winding of the marginally adjusted stop relay 516, by way of contacts of tone connecting relay 504. This upper winding is a rather ineffective winding which does not operate the relay, but produces only a slight pull so as to hasten the operation of the relay 10 responsive to operating current in the lower winding. Start relay 507 also prepares a circuit over drive-answer conductor 341 for whichever answering switch is to respond to the call, and at armature 534 it prepares a test circuit over 15 test-answer conductor 352.

Operator responds

In the event that neither of the operators is engaged at the time and the position equipment is, therefore, idle at both positions, the answering pilot lamps, such as 523 are lighted at both positions and both operators may respond to the call. The operator at the first position may respond to the call by throwing the key K1, Fig. 3, to talk-position (assuming that the link L1 is idle, as indicated by the unlighted condition of the busy lamp 336). Upon being operated to talking position, the key K1 connects the driving magnet 310 of the answering switch AS to the common drive-answer conductor 341; it connects 20 cut-through relay 301 to the common cut-through-answer and release-answer conductor 342; it opens a point in the locking circuit of ring-up relay 302 and places ground potential on the identity wiper 313; it connects the supervisory and marking wiper 314 to the common mark-answer conductor 345; it prepares a locking circuit for the link-connect relay 303 by way of the common locking conductor 344; and it 25 closes an operating circuit for the link-connect relay 203 over the common operating conductor 343, normally grounded through contacts of the talking relay 502 in the position equipment.

Link-connect relay 303 thereupon operates over conductor 343 and locks itself at its inner lower armature through contacts of the key K1 and over conductor 344, in series with talking relay 502.

Relay 502 thereupon operates and disconnects ground from conductor 343, so as to open the initial energizing circuit of the link-connect relay 303 to prevent an operation of a second link-connecting relay in case the operator should inadvertently operate another talking key.

Relay 502 also disconnects the associated talking conductors from the primary winding of the monitoring repeating coil 532 and connects them to the windings of the repeating coil 531 so as to put the circuit into talking condition, at the same time opening a point in the circuit of monitoring relay 501.

Link connected to position equipment

In the link L1, as a further result of its operation, link-connect relay 302 splits the talking conductors of the link L1 into two sections; con-

nects the answering section over tip-answer and ring-answer conductors 350 and 357 to the position talking circuit, by way of contacts of split relay 508; connects the calling end of the link circuit L1 by way of tip-call and ring-call conductors 351 and 356 to the position talking circuit through armatures 542 and 543 to the dial-answer relay 517; it joins the test and marking wipers 322 and 323 together; it connects the locking circuit of cut-through relay 304 to the common release-call conductor 353; it disconnects driving magnet 320 from the lower winding of relay 304 and the answering supervisory lamp 337; it connects the lower winding of relay 304 and answering supervisory lamp 337 to cut-through-call conductor 355; and it connects the driving magnet 320 to the common drive-call and supervisory-call conductor 354.

Operating the answering switch

The link L1 is now temporarily connected to the position equipment of Fig. 5 as pointed out above, through the operation of the talking key K1 and the link connect relay 303, and the talking relay 502 in the position equipment is operated, in addition to start relay 507.

With the circuits in this condition, the ground potential, placed on the conductor 535 at the middle upper armature of talking relay 502, is extended through contacts of split relay 508, identity relay 505, stop relay 506, and the operated start relay 507 to the common drive-answer conductor 341. Since conductor 341 is now connected through contacts of the talking key K1 and contacts of the unoperated cut-through relay 301 to the self-interrupting driving magnet 310, magnet 310 operates in a buzzer-like manner to advance the wipers 311—315 step-by-step in search of the calling circuit.

Finding the calling circuit, LD

The advance of the answering switch continues until the stop relay 506 in the position equipment becomes energized to open the above mentioned circuit of driving magnet 310. It is to be noted that ground potential is connected to the lower terminal of the test winding of the marginal stop relay 506 (from the grounded conductor 535 by way of contacts of relays 508 and 505), and that the other terminal of the test winding is connected through armature 534 of start relay 507 to the test-answer conductor 352, which test conductor is now connected through contacts of the link-connect relay 303 to the test wiper 312 of the answering switch.

The terminals encountered by the test wiper 312 in its rotation are either connected to open conductors or to grounded conductors, until wiper 312 encounters a terminal associated with a calling circuit, which terminal is supplied with battery potential. That being the case, when wiper 312 reaches the contact to which conductor 208 is connected, it encounters the battery potential impressed on conductor 208 through the upper contacts of release relay 203 of circuit LD 65 by way of resistor 205 and the upper winding of cut-off relay 204. At this time stop relay 506 in the position equipment is immediately operated to remove ground potential from the answering switch driving conductor 341 and to close a circuit for the tone-connecting relay 504. The removal of ground potential from conductor 341 opens the circuit of driving magnet 310 so as to bring the wipers 311 to 315 to rest on the terminal of the calling circuit LD. When the marginally ad- 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 Identifying the calling circuit

Justed stop relay 506 operates, it is able to remain operated without further current-flow in the lower winding, because of the above-mentioned primary current-flow in its upper winding.

5 When the tone-connect relay 504 is operated, responsive to the operation of stop relay 506, it applies battery potential through the resistor 536 to the cut-through-answer conductor 342, thereby closing a circuit through contacts of the key K1 for the cut-through relay 301. Relay 301 now operates and closes a locking circuit for itself through resistor 367 and driving magnet 310, at the same time disconnecting magnet 310 from the common driving conductor 341; it lights the busy lamp 366 at its middle lower armature; it connects up the talking wipers 311 and 315; and it places ground potential directly on test wiper 312, thereby guarding the circuit LD from further seizure.

10 In the long distance circuit LD, cut-off relay 204, which energized in parallel with resistor 205 and in series with the lower winding of stop relay 406, is maintained energized from the ground potential supplied to conductor 208 through the contacts of cut-through relay 301. Upon operating, relay 204 at its upper armature by-passes the corresponding contacts of release relay 203 and disconnects the resistor 205 to cut down current consumption; it opens the ring-back-tone circuit at its lower armature; it prepares a disconnect-supervisory circuit over conductor 209 at its inner lower armature; and at its middle lower armature it disconnects ground potential from start conductor 212 and makes an additional holding ground connection to conductor 222, so as to place the further holding of the connection built up to circuit LD under the control of the operator and to permit the calling subscriber to enjoy switchhook signalling without the danger of releasing the connection.

15 Start relay 507, Fig. 5, as well as the corresponding relay in the second position, now falls back unless another call has come in in the meantime to cause conductor 212 to become grounded at another point, in which case the two start relays remain energized for the time being.

Challenge tone

When the tone-connect relay 504 responds to the operation of stop relay 506, as above described, in addition to closing the above-mentioned circuit over conductor 342 to bring about the operation of cut-through relay 301, it opens the circuit of the upper winding of stop relay 506 so as to permit relay 506 to restore responsive to the grounding of conductor 352 at the inner upper armature of the cut-through relay 301 and through contacts of the link-connect relay 303. Stop relay 506 does not restore immediately, however, as the lower winding is short circuited by the ground connection to both its terminals. Relay 506 therefore remains operated for a momentary interval and maintains relay 504 in energized condition.

20 At its two uppermost armatures, relay 504 disconnects the operator's headset conductors from the associated talking conductors and connects them to the upper winding of the tone relay (or buzzer) 503, while at its inner lower armature it closes a self-interrupting circuit for relay 503, causing relay 503 to operate as a buzzer and thereby produce a "challenge" tone signal in the operator's receiver R, which is associated with the secondary winding of the induction coil 531 in the usual "anti-side-tone" circuit.

After a slight interval, relay 506 restores responsive to its lower winding being short circuited and its upper winding being opened. When it does so, it opens the circuit of tone-connect relay 504, whereupon relay 504 restores and terminates the momentary tone application to the operator's head-set. When relay 504 restores at this time, it applies ground potential to the upper terminal of the upper winding of identity relay 505, causing relay 505 to operate over conductor 342 and through contacts of the key K1 in parallel with the winding of cut-through relay 301, which is being supplied with holding current through driving magnet 310 and resistor 367.

When identity relay 505 operates, it disconnects ground potential from the lower terminal of this relay, and it places a battery potential on conductor lamp 346, obtained through contacts of cut-off relay 516 and resistor 538. The battery potential on lamp conductor 346 brings about the lighting of the identity lamp 331, assigned to the group of lines or circuits represented by the circuit LD, Fig. 2. This lamp is lighted through wiper 313 and contacts of talking key K1. By the lighting of lamp 331, the call is identified as a call from a local subscriber.

Waiting for a call with a talking key operated

The foregoing description explains the operation when the operator is not waiting for a call to come in. When she is not engaged, an operator may maintain a key, such as K1, thrown into talking position, in which case link-connecting relay 303 of the selected link and talking relay 502 of the position equipment are both already in operated condition when the call arrives, so that operations such as described hereinbefore take place uninterruptedly responsive to the operation of start relay 507.

Challenging the calling subscriber

Having heard the momentary application of tone current to her headset, brought about by the momentary response of tone-connect relay 504, above described, the operator now proceeds to "challenge" the calling subscriber to obtain the necessary information to enable her to complete the desired connection.

Let it be assumed that the calling subscriber calls for a number which must be reached by way of the exchange to which the toll line TL, Fig. 1, extends. In this event, the operator proceeds in a manner to be pointed out to cause the calling switch CS to position its wipers on the bank contacts associated with an idle trunk line in the group to which the trunk line TL belongs. Since the calling switch CS is a simple hunting switch and is not provided with step-by-step directive control, the operator operates the by-pass selector BPS, Fig. 6, into association with the desired group of toll lines, whereupon the by-pass selector tests the toll lines successively and locates an idle one. The calling switch CS is then caused to hunt for and find a terminal marked by the position of the by-pass selector, thus completing the desired connection.

The by-pass selector BPS, Fig. 6, is a combination one-digit and two-digit selector, operating normally as a two-digit selector, that is, the selector ordinarily responds to a level-designating digit to raise its wipers 631—635 opposite a desired level of contacts and then responds to a

group-designating digit to rotate its wipers over the contacts of the selected level into association with the first contact set in a desired group. By this arrangement, when the number of groups of toll lines is large and some of the toll line groups are small, a single level of contacts may be used to accommodate two or more toll line groups. In the event of two toll line groups being accommodated by a single level of bank contacts, an unused contact set is left between adjacent groups, so that the wipers may be driven onto this unused contact set when all trunks in the preceding group are busy, and the busy-tone signal is transmitted to the operator, while connection is not made with the next following group, as it would be if the intervening "dead" contact set were not provided.

Of the bank contacts shown in association with the wipers 634—635 of the by-pass selector, the first contact set is assumed to be set No. 1 in the first level, while the contacts shown immediately above are the first set of contacts in the second level. It is assumed that the toll-line group including the toll line TL, Fig. 1, and reached through the first level of contacts in the bank of the by-pass selector, is a small group containing less than ten toll lines, and that it, therefore, shares the first level of bank contacts in the by-pass selector with another toll-line group. Since the first toll line of the group including the toll line TL is connected to the first set of contacts in the first level, the digits 1 and 1 are assigned to this toll line group.

35 The operation of the by-pass selector

The operation of the by-pass selector to select an idle toll line and to cause the calling switch CS to connect with this toll line will now be explained.

40 Having received the desired information from the calling subscriber, the operator leaves the key K1 of the link L1 thrown into talking position (this key is a locking key, as indicated in the drawing by the letter L) and operates the dial-toll key K15 in her position equipment. When the dial-toll key K15 is thrown, it prepares a circuit at its upper contact for the bridge control relay 510 and split relay 509 in series; it bridges the impulse contacts 562 of the calling device CD across the disconnected branch of the talking conductors associated with the keys K11 to K16; and at its lower contacts it closes a circuit for selector-seizing relay 519 in series with cut-off relay 516. Cut-off relay 516 now operates to extinguish the identity lamp 331 by disconnecting the resistor 538 from the lamp conductor 346, and it disconnects the incoming start conductor 212 from start relay 507, permitting relay 507 to restore and extinguish the answering pilot lamp 523 in case the start relay 507 is still operated because of an unanswered call.

When the selector-seizing relay 519 operates, at armature 549 it transfers the drive-call and supervision-call conductor 354 from supervisory relay 511 and extends it through contacts of dial-answer relay 517 and stop relay 518 to the start conductor 553 of the by-pass selector; it lights the dial pilot lamp 524 at armature 546; and at its inner armature it grounds the holding conductor 554 extending to the by-pass selector BPS, thereby energizing the upper winding of the marginal stop relay 518 preparatory to a quick operation of stop relay 518 through 75 its more efficient lower winding.

In the by-pass selector BPS, vertical series relay 603 now operates over holding conductor 554 through off normal contacts 611 and prepares a circuit for vertical magnet 615 at its inner lower armature; it opens a point in a 5 special cut-in circuit for the rotary magnet at its lower armature; and at its upper armature it closes an operating circuit from hold conductor 554 for the cut-in relay 604. Cut-in relay 604 now operates and grounds one terminal of 10 the lower winding of line relay 601 at its inner upper armature to prepare for the operation of the line relay; it makes circuit preparations having to do with the subsequent operation of rotary magnet 616 at its lower armatures; and 15 at its upper armature it opens points in the test circuits of relays 606 and 607, at the same time closing a locking circuit for itself to conductor 554 through the upper contacts of relay 605.

As a further result of the operation of selector-seizing relay 519, armature 548 closes a holding bridge across talking conductors 557 and 558 through the retard coil 520 and the upper contacts of the bridge-control relay 510, and armatures 545 and 547 bring conductors 25 557 and 558 into connection with the tip and ring conductors 551 and 552 of the by-pass selector. As a result, when cut-in relay 604 operates as described to apply ground potential to the lower windings of line relay 601, line relay 30 601 is operated through contacts of switching relay 606 and over conductors 551 and 552 through the bridged retard coil 520. Upon operating, line relay 601 closes a circuit for release relay 602 through contacts of the test and switching 35 relays 607 and 606. Release relay 602 thereupon operates and places a shunt around the inner upper contacts of cut-in relay 604, so as to hold line relay 601 operated after relay 604 has restored. At its upper armature it connects up 40 test wiper 633 to prepare a test circuit for relay 607; and at its lower armature it opens a point in the circuit of release magnet 617 and prepares the circuit of vertical magnet 615.

The operator now manipulates the calling device CD in accordance with the first digit (1) in the number (11) assigned to the desired toll line group. When the calling device CD is moved from its normal position, the off-normal contacts 561 close the prepared circuit through the 50 upper contacts of the dial-toll key K15 for bridge-control relay 510 and split relay 509 in series. Relay 509 disconnects conductors 557 and 558 from the talking conductors of the operator's head-set and from tip-answer and ring-answer 55 conductors 350 and 357, and transfers them to the branch conductors leading to the key group containing the dial-toll key K15, whereat these conductors are connected together through the impulse contacts 562 of the calling device CD, by 60 way of contacts of the dial-toll key K15.

Bridge-control relay 510, at its upper armature, disconnects the retard coil 520 from in bridge of conductors 557 and 558, leaving the line relay 601 of the by-pass selector energized under the control of impulse contacts 562 of the calling device.

When the calling device CD is permitted to return to its normal position, the impulse contacts 562 are momentarily separated a number of times depending upon the extent to which the 70 calling device was moved, in this case one time. The line relay 601 of the by-pass selector BPS is accordingly momentarily deenergized once. Upon deenergizing, relay 601 momentarily opens the circuit of the slow-acting release relay 602 and 75

closes a circuit through contacts of the operated relays 602 and 603 for vertical magnet 615 and the lower winding of relay 603 in parallel. At this point it may be mentioned that relays 602, 603, and 605 are each provided with a copper sleeve, as indicated, so that each of these relays is slow to release, while having a minimum tendency to be slow to operate.

By the operation of vertical magnet 615, the wipers 631—635 are raised one step so that they stand opposite the first level of contacts in the associated bank. Off-normal contacts 612 prepare a circuit for release magnet 615 when the shaft of the switch is moved from its normal position, while off-normal contacts 611 open the initial circuit of vertical-series relay 603, leaving the continued operation of the relay dependent upon the momentary impulses which the lower winding of the relay receives in parallel with vertical magnet 615 during the vertical operation of the switch.

Following the delivery of the momentary impulse to the vertical magnet 615, the slow-acting vertical-series relay 603 restores and opens a point in the circuit of cut-in relay 604 at its upper armature, leaving relay 604 operated in its locking circuit which includes its own upper armature and the upper contacts of rotary series relay 605. At its lower armature, vertical-series relay 603 transfers the operating circuit from vertical magnet 615 to the rotary magnet 616, by way of the inner lower contacts of cut-in relay 604 and rotary series relay 605, preparatory to the subsequent operation of magnet 616.

When the calling device CD, Fig. 3, returns to its normal position, contacts 561 separate to permit relays 510 and 509 to restore. Relay 510 restores immediately to re-establish the holding bridge through retard coil 520, while split relay 509 restores a moment later.

When the operator manipulates the calling device CD in accordance with the second digit (1) of the number (11) assigned to the toll line group, the above operations are repeated, with the result that line relay 601 is again momentarily de-energized. This time, relay 601 momentarily closes a circuit through the lower armature of the operated relay 602, the lower armature of the restored vertical-series relay 603, and the lower armature of the operated cut-in relay for rotary magnet 616, by way of rotary series relay 605. Relay 605 is operated in series with the rotary magnet to establish a new circuit for itself and for the rotary magnet, independent of the inner lower contacts of cut-in relay 604; it opens a point in the hunting circuit of rotary magnet 616 at its inner lower armature; and at its upper armature it opens the locking circuit of cut-in relay 604, permitting relay 604 to restore and prepare the hunting circuit of magnet 616.

By the operation of magnet 616 responsive to this impulse, the wipers 631—635 are brought into engagement with the first set of contacts in the selected level, which in this case is the contacts terminating the conductors 361—365.

At the end of a slight interval following the rotary movement, slow-acting series relay 605 restores to start the hunting operation. Upon doing so, relay 605 opens the directive circuit of the rotary magnet at its lower armature; applies ground potential at its two upper armatures to the test windings of the switching and test relays 606 and 607; and at its inner lower armature completes a self-interrupting circuit for rotary magnet 616 by way of the self-interrupting contacts of magnet 616, inner lower armatures of relays 604 and 605, contacts of the operated line relay 601, and the lightly adjusted contacts of switching relay 606 and test relay 607. The contacts labeled "X" are so located as to be the first to operate when the armature, proper, of the relay starts to move. The hunting action of the by-pass selector BPS now takes place pursuant to the location of an idle toll line in the selected group. This hunting action proceeds until one or both of the relays 602 and 607 is operated responsive to the encountering of a battery potential by wipers 633 and 634.

All lines busy in the selected group

tacts of magnet 616, inner lower armatures of relays 604 and 605, contacts of the operated line relay 601, and the lightly adjusted contacts of switching relay 606 and test relay 607. The contacts labeled "X" are so located as to be the first to operate when the armature, proper, of the relay starts to move. The hunting action of the by-pass selector BPS now takes place pursuant to the location of an idle toll line in the selected group. This hunting action proceeds until one or both of the relays 602 and 607 is operated responsive to the encountering of a battery potential by wipers 633 and 634.

All lines busy in the selected group

In the event that all of the lines in the selected group are in use, the rotary movement continues until the wipers 631—635 have been rotated entirely over the group and have arrived on the set of inter-group contacts. The pair of inter-group contacts engaged by wipers 634 and 635 are strapped, or connected together, with the result that an energizing circuit is completed by way of the resistor 609 and lower contacts of line relay 601, wipers 635 and 634 (interconnected by the strap on the bank contact they are now engaging), and contacts of relays 607 and 606. When relay 606 energizes it breaks the self-interrupting circuit of magnet 616 at its lower contacts, while at its upper contacts it makes a connection from the associated, common busy-tone conductor 636 to the tip conductor 551, and it grounds conductor 532 to form a return circuit for the busy tone current, thus informing the operator of the busy condition. Relay 606 also performs the switching-through operation, which will be explained subsequently.

In the event that the last group in the level is being called, the wipers 631—635 are rotated entirely off the contact bank when they leave the last line in the group, whereupon overflow contacts 614 are operated to close a circuit for switching relay 606 and cause the operator to be informed of the busy condition.

Seizing the idle toll line TL

For the purpose of describing how the call now in progress is completed, it will be assumed that the toll line TL, Fig. 1, is idle when the wipers 631—635 are brought into engagement with the first set of bank contacts in the first level, responsive to the dialling of the second digit 1. In this event, test wiper 633 encounters a battery potential, placed on conductor 363 through the resistor 105 and relay 103, in parallel and contacts of relay 102. As a result of this encountering of battery potential by test wiper 633, test relay 607 is energized in a circuit from the grounded holding conductor 564, through contacts of relays 605, 604, and 602. Upon operating, relay 607 quickly breaks the hunting circuit of magnet 616 at armature 642; at the same armature it places ground potential directly on test wiper 633 so as to mark the toll line engaged; it closes a locking circuit for its lower winding at its inner lower armature from the grounded holding conductor 544 through contacts of relays 605 and 604; at armatures 643 and 644, it connects up wipers 634 and 635; and at armature 641 it closes an energizing circuit for the two windings of switching relay 606 in series, whereupon relay 606 operates.

Upon operating, relay 606 disconnects the incoming tip and ring conductors 551 and 552 from the windings of line relay 601, and extends them through wipers 631 and 632, and by way of talk-

ing conductors 361 and 362 to the talking conductors of the toll line TL, thereby placing the operator immediately into telephonic connection with the toll line.

5 Line relay 601 restores because it is disconnected by relay 606, and release relay 602 restores also. Relays 601 and 602 prepare a circuit for release magnet 617, but the release-magnet circuit is maintained open at armature 642 of relay 10.

10 607 and at the lower contacts of relay 606.

In the toll-line circuit TLC, responsive to the ground potential being placed on sleeve conductor 363, cut-off relay 103 operates and extends the grounded conductor 363 to cut-off conductor 108,

15 extending to the bank of the answering switches such as AS, thereby causing the toll line TL to test busy in the banks of the answering switches. Relay 103 also disconnects the resistor 105 from in multiple with its own winding, as this resistor is

20 no longer needed for the duration of the present call; it closes a point in the chain circuit of the group busy lamp; it opens the line-relay bridge at the upper armature; and at its lower armature

25 it applies ground potential to the junction of resistor 104 and signal relay 102, which operation is of utility in restoring the signal relay when an incoming call over the toll line TL is answered.

Having thus obtained connection with an idle toll line in the desired group, the operator may 30 proceed to operate her ringing key so as to signal the operator at the distant toll board in a manner to be explained fully subsequently.

The calling switch CS operates

35 While the operator is proceeding to signal the distant operator the calling switch CS of the link L1 is caused to operate as a finder until it finds the toll line TL, to which connection has been made by the by-pass switch BPS, Fig. 6.

40 Upon the above-described operation of test relay 607 of the by-pass selector, start conductor 533 is grounded at the inner upper contacts of relay 607, thereby extending a ground potential by way of the upper armature and testing contact

45 of stop relay 518, armature 544 and its resting contact, and armature 549 of the selector seizing relay 519, to drive-call conductor 354. The ground potential on conductor 354 is extended by way of contacts of the operated link-connect relay 303, and the middle lower armature and resting contact of cut-through relay 304 to the driving magnet 320 of the calling switch CS. Self-interrupting magnet 320 now operates in a buzzer-like manner to drive the wipers 321-325 until

55 the circuit of the magnet is opened when stop relay 518 energizes responsive to the arrival of the wipers upon the contacts assigned to the toll line TL with which the by-pass selector BPS is now connected.

Switch CS finds toll line TL

When the wipers 321-325 arrive on the contacts to which conductors 361, 363, 364, and 362 (associated with the toll line TL) are connected, 60 test wiper 322 encounters the ground potential placed on the sleeve conductor 363 of toll line TL by way of wiper 633 and armature 642 of the by-pass selector BPS. This ground potential is thereby extended through wipers 322, middle upper armature and resting contact of cut-through relay 304, contacts of the operated link-connect relay 303, and marking test wiper 323 to the marking conductor 364. Marking wiper 634 of the by-pass selector is now in engagement with the bank 70 contact of which conductor 364 is connected,

whereby a circuit is closed through armature 343, over conductor 555, and through contacts of dial-answer relay 517 for the lower winding of the marginal relay 518. Relay 518, which is partially energized (because of the circuit closed through its low-efficiency upper winding from the grounded hold conductor 554), operates quickly when current flows through its lower winding. Upon operating, relay 518 disconnects the start conductor 553 from drive-call conductor 354. 10 Magnet 320 of the calling switch CS therefore ceases to operate, and the wipers 321-325 remain in association with the toll line TL.

Cut-through relay 303 operates

15 When stop relay 518 disconnects start conductor 553 from drive-call conductor 354, it extends it through contacts of relay 517 and the lower winding of signal relay 514 to cut-through-call conductor 355, now connected through contacts of link-connect relay 303 to the lower winding of the cut-through relay 304 associated with the calling switch CS. Relays 514 and 304 energize in series over this circuit, but the energization of relay 514 does not appear to have 25 any particular utility at this time.

When cut-through relay 304 operates, it closes a locking circuit for itself at its inner upper armature through the resistor 364; disconnects the drive-call and supervisory-call lead 354 from 30 magnet 320 and connects it to the supervisory wiper 324; closes an additional circuit for the busy lamp 336; disconnects test wiper 322 from the marking wiper 323 and connects it to ground, so as to maintain the toll line guarded after the 35 by-pass selector has released; and at its upper and lower armatures it connects up the wipers 321 and 325.

The telephonic connection has now been built up from the calling long distance circuit LD, 40 through the link L1, to the toll line TL, and it now includes the talking conductors in the position equipment, Fig. 5, because of the operated condition of the link-connect relay 303.

Signaling the distant operator

45 As soon as the operator has dialed the number of the toll line, she manipulates the ringing key K11 to ring out on the calling end of the circuit. The lower spring combination of the key 50 K11 applies ringing current to the associated ring conductor; the inner upper contacts of the key apply ground potential to the associated tip conductor; and the upper contacts of the key apply ground potential (obtained through contacts of the dial-answer key K13) to the conductor associated with bridge control and split relays 510 and 509. Relay 510 operates to open the control bridge across conductors 557 and 558 including the retard coil 520, while the split 60 relay 509 operates to transfer conductors 551 and 558 to the branch conductors associated with the keys K11 to K16. The ringing current is therefore transmitted to the tip and ring conductors of the toll line TL by way of the connection set up through the by-pass selector BPS.

65 As soon as the calling switch CS has been positioned on the toll line TL as above described, a new path for the ringing current is closed through armatures 542 and 543, over tip and ring 70 conductors, 351 and 356 of the cable C3, and thence to the toll line through contacts of the operated link-connect relay 303 and wipers 321 and 325.

75 When the operator restores her ringing key

K11, the application of ringing current is terminated and relays 509 and 510 are permitted to restore.

When the distant toll operator responds, she 5 may converse with the originating toll operator and be informed of the destination of the call, whereupon she proceeds to complete the desired connection.

10 Restoring the by-pass selector

Having conversed with the distant operator, the originating operator now releases the by-pass selector BPS. She does this by restoring the dial-toll key K15. At the lower contacts of the 15 key, the circuit of relays 519 and 516 are opened, whereupon these relays both restore, and relay 516 again permits start relay 507 to be controlled over start conductor 212.

When selector-seizing relay 519 restores, it 20 disconnects the tip and ring conductors 557 and 558 from the corresponding conductors 551 and 552 of the by-pass selector, as well as opening the holding bridge across conductors 557 and 558 through the retard coil 520. Relay 519 also 25 disconnects holding ground from conductor 554, whereupon switching and test relays 606 and 607 restore. Relay 607 removes ground potential from start conductor 553, whereupon relay 514 restores but cut-through relay 304 remains operated over its locking circuit including resistor 366.

Switching and test relays 606 and 607 disconnect the wipers of the by-pass selector and they 30 close a circuit through armature 642 and its resting contact, contacts of relay 606, and the lower contacts of line and release relays 601 and 602, for release magnet 617, by way of off normal contact 612. Release magnet 617 operates and causes the by-pass selector BPS to be restored to its normal position, whereupon the release-magnet circuit is open at off-normal contacts 612.

Stop relay 518 restores when the circuit of its upper winding is opened by the removal of ground potential from hold conductor 554 at the inner contacts of relay 519.

45 The operator permits her key K1 to remain in talking position to maintain the link-connecting relay 303 operated until the connection has been extended to the desired line and a response has been secured, or until it has been determined that a response cannot be secured immediately, if such is the case. In the latter case, the operator 50 ordinarily requests the calling subscriber to replace his receiver and wait until he is called back, and the connection is later completed as a delayed 55 call.

The called subscriber answers

When the distant subscriber responds, the originating toll operator makes note of the time 60 of the response so that she may determine the length of the conversation.

Operating the split keys

In case the operator desires to converse with 65 the calling subscriber while the talking circuit toward the called subscriber is maintained open, she operates the split-call key K12, operating the split relay 509 to disconnect the two sections of the link circuit L1 from each other, leaving the 70 answering section of the link circuit connected to the operator's headset. On the other hand, if the operator desires to converse with the operator at the distant toll board or with the called subscriber without the conversation being heard 75 by the calling subscriber, she operates her split-

answer key K6, operating split relay 508 to disconnect the answering end of the link circuit L1 from the operator's headset, leaving the operator's headset connected to the calling end of the link circuit L1. Relay 508 of course restores and 5 again completes the talking circuit between the two ends of the links L1 when the split key K6 is restored.

Freeing the position equipment

10

After making sure that the two subscribers are telephonically connected, the operator restores the key K1. When this key is restored, the link-connect relay 303 in the link circuit L1 and talking relay 502 in the position equipment both restore, but the cut-through relays 301 and 304 remain energized to maintain the talking circuit 15 complete through the link circuit L1. When the link-connect relay 303 restores, the talking circuit is confined to the link circuit L1, passing through 20 contacts of the link-connect relay, and the temporary association between the operator's position equipment of Fig. 5 and the link circuit L1 is terminated.

It is to be noted that the talking relay 502 in 25 the position equipment re-applies ground potential to pick-up conductor 343, so as to enable the operator now to energize the link-connect relay (such as 303) in any link circuit when the talking key in such link circuit is thrown.

30

Monitoring the connection

In the event that the operator desires to monitor the connection to ascertain whether or not the two subscribers are conversing properly, she 35 throws the key K1 of the link L1 into monitoring position, thereby connecting conductors 347 and 348 to the talking conductors in the link and placing a ground potential on conductor 349. The placing of ground potential on conductor 349 40 closes a circuit through contacts of the talking relay 502 for the monitoring relay 501. Relay 501 disconnects the receiver R of the operator's headset from its normal position in the circuit and associates it with the secondary winding of 45 the stepdown monitoring transformer 532, whereby an efficient monitoring circuit is formed which enables the operator to listen in on the circuit while taking a minimum amount of voice current energy therefrom. The monitoring relay 501 restores when the key K1 is restored.

It is to be noted that the conductors leading to the chief operator's equipment COE, Fig. 5, part 1, are normally connected across the regular talking leads of the operator's headset, but are 55 switched into parallel relationship with the receiver R when the monitoring relay 501 is operated. By this arrangement, the chief operator is enabled to listen in with the operator at position 1 at any time to exercise her supervisory functions.

Changing toll lines

Provisions have been made for enabling the operator to substitute a toll line for one involved 65 in an inter-exchange connection when it appears that the connection set up through a toll line is faulty. This substitution may be made when the connection is originally extended to the distant exchange and while the operators are conversing 70 pursuant to the final extension of the connection to the called line, or the poor transmission qualities of the toll line may not become evident until the two subscribers start to converse with each other. The originating operator may ascertain 75

the quality of the transmission between the two subscribers by the use of her monitoring key, as above pointed out. Alternatively, the calling subscriber may signal the operator by manipulating his switchhook, causing the calling supervisory lamp 335 to flash in a manner to be pointed out hereinafter. On the other hand, the distant toll operator may be the first to become aware of the faulty transmission and she may signal the originating toll operator by ringing current, causing the ring-up relay 302 to operate and light the calling supervisory lamp 335 and lock under the control of the talking portion of the key K1. For the purpose of the description, however, it will be assumed that the originating operator herself discovers the faulty transmission, whereupon she may operate her talking key K1 and bring about the reoperation of the talking relay 502 and the link-connect relay 303 to bring her into telephonic communication with the two subscribers. She may then explain to the two subscribers that she is about to secure a better connection for them, requesting the two subscribers to wait.

As the next step, the originating operator may operate the ring-call key K11, bringing about the operation of the split relay 509 to permit ringing current to be transmitted over the tip and ring conductors 351 and 356, through contacts of the operated link-connect relay 303, and through wipers 321 and 325 to the toll line TL. This application of ringing current signals the distant operator, whereupon she comes into telephonic communication with the toll line and converses with the originating operator.

Assuming that the exchange to which the toll line TL extends is an automatic exchange and equipped with the new toll switchboard disclosed herein, each operator proceeds in about the same way to select another toll line. The originating operator manipulates her dial-toll key K14, to bring about the hereinbefore described operation of selector seizing relay 519 and cut off relay 516. The by-pass selector BPS is again seized and prepared for operation. At this time, as before, the operator dials the number 11 assigned to the toll-line group, causing the by-pass selector to select the first idle line, the second line in the group, for example. By a similar operation, the distant operator makes connection with the same toll line, as her by-pass selector will also select the first idle toll line in the group.

While still maintaining the dial-toll key K15 operated, the operator throws the release-call key K14 to break the connection between the calling switch CS of the link L1 and the toll line TL. Release-call key K14 in addition to operating the bridge control and split relays 510 and 509 places a ground potential on release conductor 353, shunting the locking winding of cut-through relay 304 and causing this relay to restore. When relay 304 restores, the operating magnet is again connected through contacts of the operated link-connect relay 303 to drive-call conductor 354, now connected through the operated armature 549 of relay 519 to start conductor 553, grounded in the by-pass selector. The calling switch CS therefore hunts for and connects with the toll line selected by the by-pass selector. The release call key K14 is restored to permit cut-through relay 304 to become locked again when it reoperates over its lower winding and cut-through-call-conductor 355, when stop relay 518 is reoperated to break the hunting circuit of the calling switch and to energize the cut-through-call circuit.

The line of the called subscriber having likewise been connected to the new toll line at the distant end thereof, the conversation between the two subscribers may now be resumed, and the originating operator clears her position equipment by restoring key K15, as well as key K1 in the link L1.

Clearing out after conversation

At the end of the conversation, the two subscribers replace their receivers. When the receiver is replaced at the calling substation, line and release relays 202 and 203 of the long-distance circuit LD, Fig. 2, restore, but cut-off relay 204 remains operated over conductor 208, there- 15 by maintaining release trunk conductor 222 grounded to hold up the connection for the time being. With relay 202 restored, a circuit is closed through contacts of relays 202 and 204 and over conductor 208 for the calling supervisory lamp 20 335, by way of wiper 314 and contacts of cut-through relay 304. Lamp 335 is now lighted steadily as a disconnect signal.

Freeing the local line immediately

Upon perceiving the disconnect signal, the operator may proceed to free the line of the calling subscriber immediately by clearing out the answering switch AS. To do this, the operator again throws the talking key K1 to bring about the operation of the link-connect relay 303 of the link L1 and the talking relay 502 of the position equipment, following which the operator throws the release-answer key K8. The release answer key K8 operates the split-answer relay 35 508, and it places a ground potential on release-answer conductor 342, which closes a shunt, through contacts of the talking key K1 in the link circuit, around the winding of cut-through relay 304, causing this relay to restore and open the 40 connection between the link and the calling line. Resistor 357 limits the current flow through the shunt circuit to prevent a spurious operation of magnet 310.

When cut through relay 304 restores and removes ground potential from test wiper 312 and therefore from conductor 208, cut-off relay 204 of the long distance circuit LD restores and removes ground potential from release trunk conductor 222, permitting the switching apparatus 50 between the calling line and the circuit LD to restore and free the subscriber's line for further use.

Clearing out the called end of the connection

Having momentarily operated the release-answer key K8 to clear out the calling end of the connection, the operator now throws her ringing key K11 to signal the distant operator. It will be recalled that the operation of key K11 results 60 in the operation of slit relay 509 to connect the branch associated with the key K11 to conductors 557 and 558, so that the ringing current passes over the called end of the connection by way of armatures 542 and 543 of the dial 65 answer relay 517, conductors 351 and 356, contacts of the link-connect relay 303, contacts of the cut-through relay 304, and the wipers 321 and 325 of the calling switch CS.

When the distant operator responds to the 70 momentary application of ringing current, the two operators converse and the distant operator is told to clear out the connection.

The originating operator now releases the calling end of the connection by momentarily oper- 75

ating the release-call key **K14**. Key **K14** operates the bridge-control and split relays **519** and **509**, and it places a ground potential on release-call conductor **353**, thereby closing a shunt circuit (through contacts of link-connect relay **303**) around the upper winding of cut-through relay **304**. Relay **304** is caused to restore and disconnect the called end of the connection. The resistor **366** prevents a harmful rush of current when the shunt circuit is established.

The operator now restores her key **K1**, bringing about the restoration of the link-connect relay **303** and the restoration of talking relay **502**.

Operations when the desired connection cannot be completed immediately

In the event that the operator receives a call as described, over the long-distance circuit **LD**, for example, and cannot complete it on the first attempt, (the line may be busy, or the called subscriber may not be at home) she may request the calling subscriber to wait on the line, or she may inform him that he may "hang up" and be recalled when the connection is ready. Assume now that the calling subscriber has replaced his receiver while waiting for the connection to be completed, and that the connection has been completed to the desired line and a response has been secured. The operator may request the called subscriber to wait a moment. She then operates the ring-answer, local, key **K4** to recall the calling subscriber. The key **K4** operates split relay **508** to associate tip-answer and ring-answer conductors **350** and **351** with the key; it connects a ringing-current lead to ring-answer conductor **357**; and it connects the ungrounded pole of the exchange battery to the tip-answer conductor **350**. Assuming that the link circuit **L1** is the one in use, the conductors **350** and **357** are connected through the switch **AS** to the long-distance circuit **LD**, which is still connected to the calling line. Therefore ringing relay **201** responds to the potential placed on the associated tip conductor. Upon responding relay **201** opens the bridge including the right-hand repeating-coil windings; it transfers the incoming tip conductor **221** to ground to afford a return path for ringing current, and it transfers incoming ring conductor **223** to ring conductor **210**, thereby permitting ringing current to pass from conductor **210** to conductor **223**, and thence to the called line.

When the key **K4** is restored, the application of ringing current ceases, and split relay **508** restores, as does ringing relay **201** of circuit **LD**.

When the calling subscriber responds, line relay **202**, which restored when he "hung up" and thereby lit lamp **335**, reoperates and extinguishes the lamp.

The conversation may now proceed.

In passing, it may be noted that the ring-answer, toll, key **K15** is used when the operator wishes to ring over a toll line connected with **65** by the answering switch of a link.

An incoming call

In order to explain how a call incoming from another exchange is completed through the toll board to a local line, it will be assumed that the distant toll operator in the exchange to which the trunk line **TL**, Fig. 1, extends, has received a call for a subscriber of the exchange served by the illustrated toll board, and that the distant operator has extended a connection to the trunk line

TL in the distant exchange and has applied ringing current momentarily to the trunk line.

In the toll-line circuit **TLC**, line relay **101** (bridged across the conductors of the toll trunk **TL** through contacts of cut-off relay **103** and through the associated condenser) responds to the ringing current by vibrating its contacts. A vibration of the contacts of line relay **101** results in the opening of the shunt circuit normally existing around the winding of signal relay **102**. When this shunt circuit is opened, signal relay **102** operates in series with resistor **104** and opens another point in the shunt circuit at its lower armature; it disconnects conductor **363** from the winding of cut-off relay **103** and connects it to ground at its upper armature so as to mark the toll line engaged in the banks of the by-pass selectors; it marks the toll line **TL** as a calling line by applying battery potential by way of cut-off relay **103** and resistor **104**, in parallel, to conductor **108**; and at its lower armature it grounds the start conductor **212** to signal an operator through an answering pilot lamp, such as lamp **523**, Fig. 5, part 1, or to automatically start an answering switch such as the answering switch **AS** in search of the calling line if an operator has a talking key such as the key **K1** thrown on an idle link in readiness for a call to come in automatically to the operator's headset.

*Finding the calling circuit **TLC***

It will be assumed that the link circuit **L1** is the one selected at the first position to take care of the next call and that its answering switch **AS**, upon operating in the manner hereinbefore described, arrives on the terminals of the toll line **TL** before an answering switch in the second position does so. Under this condition, stop relay **506** of the position equipment is operated to terminate the hunting movement, in a circuit over test-answer conductor **352**, contacts of the link-connect relay **303**, test wiper **312**, conductor **108**, contacts of the operated signal relay **102**, and the resistor **105** and cut-off relay **103**, in parallel. As before described, the operation of stop relay **506** results in a momentary operation of tone-connect relay **504** to give the operator an audible indication, and to place a battery potential on cut-through-answer conductor **342** by way of the resistor **536** to operate cut-through relay **302** through contacts of the key **K1**. Cut-through relay **301** thereupon lights the busy lamp **336** and connects up the wipers of the answering switch **AS**.

In the toll-line circuit **TLC**, cut-off relay **103** is operated to open the line-relay bridge, to lock itself to conductor **108** and disconnect resistor **105**, and to shunt the signal relay **102** so as to restore it and thereby remove ground potential from the start conductor **212**.

Selecting a toll service circuit

Upon conversing with the distant operator and finding that the call is to be completed to a subscriber of this exchange, the operator causes the calling switch **CS** of the link circuit **L1** to be brought into association with an idle toll-service circuit, such as the toll service circuit **TSC**, Fig. 4, through which the connection may be set up. To do this, the operator throws her dial-automatic key **K16**. In addition to associating the calling device **CD** with the circuit, key **K16** at its upper contacts operates start relay **515** in series with cut-off relay **516**.

At its lower armature, start relay **516** applies

ground potential by way of the lower winding of stop relay 513 to group-mark conductor 358, which is multiplied to all of the contacts in the banks of calling-switch marking wipers, such as wiper 323, 5 that are associated with toll-service trunks. This prepares a circuit for stopping the calling switch CS on the contacts of an idle toll-service trunk. Start relay 515 also closes a circuit at its inner upper armature through contacts of signal relay 10 514 for the upper winding of the marginal stop relay 513, so as to partially energize relay 513 and prepare it to operate very quickly when the circuit prepared through its lower winding and over group-mark conductor 358 is completed. A 15 branch circuit, in multiple with the upper winding of relay 513, operates bridge-control relay 510 and split relay 509 in series. Split relay 509, in addition to transferring conductors 557 and 558 to the branch conductors leading to the key set, now 20 extends ground potential from conductor 535 (grounded at the contacts of the energized talking relay 562) through contacts of the operated start relay 513, and contacts of the unoperated stop and signal relays 513 and 514 and by way of armature 549 to drive-call conductor 354. The placing 25 of the ground potential on conductor 354 at this time closes a circuit through contacts of the operated link-connect relay 303 and through contacts of cut-through relay 304 for the self-interrupting 30 driving magnet 320. Bridge-control relay 510 disconnects drive-call conductor 354 from cut-through call conductor 355 (normally interconnected through supervisory relay 511).

Magnet 320 operates in a buzzer-like manner to 35 drive the wipers 321—325 until they arrive on the contacts of an idle toll-service trunk, the trunk extending to the toll service circuit TSC, Fig. 4, for example. When this trunk is reached, wiper 322 encounters battery potential on conductor 40 372, applied through resistor 405 in the toll-service circuit TSC. This battery potential is extended through wiper 323, (connected to wiper 322 through contacts of link-connect relay 303) to group-mark conductor 358. Stop relay 513 is 45 therefore operated over conductor 358 to remove ground potential at its upper armature from drive-call conductor 453, thereby permitting the operation of magnet 320 of the calling switch CS, and heaving the wipers 321—325 in engagement 50 with the bank terminals to which conductors 371—374 are connected.

Stop relay 513 also operates cut-through relay 512 at its inner upper armature, whereupon relay 512 extends ground potential over cut-through-call conductor 355 and through contacts of relay 383 to cut-through relay 304. Cut-through relay 304 operates and connects up the associated wipers, locking itself energized at its inner upper contacts through the resistor 366.

Stop relay 513 also closes a circuit for the upper winding of signal relay 514, which includes contacts of the operated relays 515, 509, and 502. Upon operating, relay 514 locks itself at armature 541 through contacts of relay 515; at armature 540 it opens an additional point in the circuit through which ground potential was previously applied to conductor 354; and at its inner upper contacts it opens the circuit of the upper winding of relay 513 and the circuit of relays 510 and 509. Relays 510 and 509 restore, and relay 513 restores 65 also, as its circuit over conductor 358 has been opened at contacts of the cut-through relay 304. Cut-through relay 512 is restored by relay 513.

At its upper armature, signal 514 closes a circuit 70 for the dial-pilot lamp 524 to inform the operator

that she may now operate the dial of the calling device CD in accordance with the digits in the desired number.

Seizure of the toll service circuit

5

When the supervisory wiper 324 is connected up at the contacts of cut-through relay 304, a circuit is closed over supervisory conductor 373 for switching relay 401 in the toll service circuit TSC. This circuit includes contacts of the operated link-connect relay 303, supervisory-call conductor 354, armature 549 and its resting contact, contacts of the bridge-control relay 510, supervisory relay 511, and resistor 537. Relay 511 does not operate over this circuit in series 15 with the high resistance upper winding of relay 401. The lamp 337 is therefore not now lighted.

In the toll service circuit TSC, when relay 301 operates over supervisory lead 373, it opens the by-pass connections around the windings of the 20 repeating coil 402, bridging the left-hand repeating-coil windings across the incoming conductors 371 and 374, and bridging the right-hand repeating-coil windings across the outgoing conductors 406 and 408. The line relay (not shown) of the 25 toll service selector to which conductors 406—408 extend, now operates over conductors 406 and 408 in series with the lower winding of electro-polarized supervisory relay 403 to prepare the toll-service selector for operation. The polarizing winding of relay 403 is energized from the grounded release-trunk conductor 372 through contacts of the operated relay 401 and resistor 409. The current now flows through the lower winding of supervisory relay 403 in such a direction as to oppose the polarizing winding of the relay. Relay 403 therefore does not now operate.

Dialing the desired number

When the operator turns the calling device 40 CD from its normal position, the off-normal contacts 561 close a circuit through contacts of the key K16 for bridge-control relay 510 and split relay 509 in series. Relay 509 operates to connect conductors 557 and 558 to the impulse contacts 562 of the calling device CD, and bridge-control relay 510 disconnects the battery potential (applied by way of resistor 537 and supervisory relay 511) from drive-call and supervisory-call conductor 354, thereby opening the circuit of switching relay 401 in the toll service circuit TSC, Fig. 4.

Relay 401 by-passes the windings of the repeating coil 402 and opens both the front and back bridges of the circuit TSC, so that incoming conductor 371 is extended through contacts of relay 401 to conductor 408, and the incoming conductor 374 is extended through contacts of relay 401 to the outgoing conductor 406.

The line relay (not shown) of the toll service selector to which conductors 406 and 408 extend is now held operated over conductors 371—374, wipers 321 and 325, contacts of the link-connect relay 303, tip-call and ring-call conductors 351 and 356, armatures 542 and 543, conductors 557 and 558, contacts of the operated split relay 509, contacts of dial-automatic key K16, and the impulse contacts 562 of the calling device CD. This transfer is made, it will be noted without any interruption in the continuity of the circuit extending to the line relay of the toll service selector, as the split relay 509 operates first to prepare the circuit while switching relay 401 of the toll-service circuit transfers the line relay from the holding bridge (through relays 403) through 70 75

make-before-break contacts to the incoming conductors 371 and 374.

As the calling device CD, Fig. 5, returns to its normal position, it interrupts the control circuit a number of times depending upon the value of the digit for which the calling device was operated.

When the calling device again reaches normal position, relays 510 and 509 restore successively.

10 Relay 510 again applies a battery potential through resistor 537 and the winding of the marginal supervisory relay 511 to conductor 354, bringing about the above described operation of switching relay 401.

15 The same operations are repeated each time the calling device CD is operated in accordance with a succeeding digit in the desired number.

Idle-line supervision

20 After the final digit has been dialed, and the connection has been finally completed to the called line, and in the event that the called line is idle, current-flow is reversed in the well known manner in the conductors 406 and 408 outgoing from toll service circuit TSC, whereupon the electro-polarized supervisory relay 403 operates and removes the shunt from around the winding of the supervision-repeating relay 404. Relay 404 now operates and shunts the low resistance lower winding of relay 401 around the high resistance upper winding of the relay, thereby so increasing the current-flow over conductor 373 and through the marginal supervisory relay 511 to cause relay 511 to operate and bring about the 30 operation of cut-through relay 512. Relay 512 applies ground potential to cut-through-call conductor 355, thereby lighting supervisory lamp 337 through contacts of relay 303 to indicate that the called line is idle and that connection has been made thereto.

40 The operator may now converse with the originating operator and discover whether or not the originating operator is ready for the called subscriber to be signalled.

45 When the called subscriber is to be signalled, the operator manipulates the ring-call key K11, thereby applying ringing current to the associated branch of the talking conductors and operating bridge-control and split relays 510 and 509 through contacts of the unoperated dial-answer key K13. Bridge-control relay 510 opens the supervisory and bridge-control circuit at its inner upper armature, whereupon relay 401 of the toll service circuit TSC and relay 511 in the position equipment both restores. Relay 511 restores cut-through relay 512 to extinguish the supervisory lamp 337, and relay 401 clears the circuit TSC for the through passage of ringing current.

50 Responsive to this application of ringing current, the usual automatic ringing is started, whereby the called subscriber is signalled in the usual manner.

55 When the ring-call key K11 is restored, relays 509 and 510 restore, and relays 511, 512, and 401 reoperate, and lamp 337 is relighted.

Answering supervision

60 When the called subscriber responds, the usual ring-cut-off operation takes place, and current-flow in the outgoing conductors of the trunk circuit TSC is discontinued for the period of the conversation. At this point supervision-repeating relay 404 falls back to extinguish lamp 401. This indication is relayed by supervisory relay 511, which restores and thereby causes relay 512

to restore and finally extinguish lamp 337 to give answering supervision.

The operator may now restore her talking key K1, and thereby restore link-connect relay 303, whereby her position equipment is freed and cleared out for further use in association with other links.

With the link-connect key restored, voice currents may pass directly through the strands of the link L1 without traversing the position equipment. Moreover, the answering-supervisory lamp 337 is now connected directly to the supervisory wiper 324, through contacts of the operated cut-through relay 304 and contacts of the restored link-connect relay 303. From this point 15 on, lamp 337 is light or not, depending upon whether the supervision-repeating relay 404 is operated or not, as the lamp will not glow in series with the upper winding of relay 401.

Having caused the connection to be completed 20 in the manner above pointed out, the operator proceeds with her other duties and pays no further attention to the established connection until she receives a disconnect or a recall signal.

Changing toll lines

25 In order to explain how the operator is able to change toll lines when the toll line in use proves to be defective for conversational purposes, it will be assumed that the distant operator, upon listening in during conversation, discovers that the transmission over the toll line TL is faulty. Under this condition, the distant operator projects ringing current over the toll line TL to operate the bridged ring-up relay 302 in the link circuit 30 L1. Relay 302 operates and locks itself through contacts of the key K1, at the same time closing a lighting circuit for the calling-supervisory relay 335.

35 When the operator throws the key K1 to talking position, so as to energize the link-connect relay 334 and the talking relay 502 in the position equipment, ring-up relay 302 is restored and the calling supervisory lamp 335 becomes extinguished. The distant toll operator then informs 40 the completing operator of the faulty condition of the toll line TL and requests her to make connection with another toll line in the same group so that the connection may be rerouted over the other toll line. In order to do this, the operator 45 proceeds in somewhat the same manner as hereinbefore described to position the by-pass selector BPS on the first idle toll line in the group including the toll line TL and to cause the answering switch AS to be repositioned on the new toll 50 line. Since she now desires to reposition the answering switch AS, the operator throws the dial-answer key K13. The dial answer-key K13, in addition to making the connections made by the dial-tone key K17 closes a circuit for dial-answer 55 relay 517 in series with cut-off relay 516. As a result, relays 516, 517, and 519 are now operated, and relay 519 brings about the seizure of the by-pass selector BPS and the preparation of this selector for operation. Relay 517, at its lower armature, prepares a new energizing circuit by way of the resistor 539 for cut-through-answer conductor 342; disconnects the test winding of the stop relay 518 from the mark-call lead 555 and connects it to the mark-answer lead 556, so as 60 to mark a conductor in the bank of the answering switch AS instead of in the bank of the calling switch CS; at armature 544 it transfers start conductor 553 into association with the drive-answer lead 341; at its inner upper armature it 65

70 connects the test winding of the stop relay 518 to the mark-call lead 555 and disconnects it from the mark-answer lead 556, so as 75 to mark a conductor in the bank of the answering switch AS instead of in the bank of the calling switch CS; at armature 544 it transfers start conductor 553 into association with the drive-answer lead 341; at its inner upper armature it 75

- disconnects the cut-through-call lead 355 so that it will not become grounded upon the operation of stop relay 518; it disconnects the tip-call and ring-call conductors at armatures 542 and 543 so as to isolate the called substation for the time being; and at its upper armature it grounds the mark-answer conductor 345 so as to enable the marking circuit to be subsequently completed by way of wiper 314 of the answering switch AS.
- 10 It is to be noted that ground potential is now removed from the upper contact pair of the ring-call key K11 and of the ring-answer key K5, so that neither of the ringing keys K5 and K11 is able to operate its associated split relay (508 and 509), and the operator is now unable to ring out over either end of her position equipment.

When the operator manipulates her calling device CD in accordance with the two-digit number assigned to the toll line group including the toll line TL, the by-pass selector BPS operates as hereinbefore described to search over the group. It will be assumed now that the second toll line in the group is idle. The second toll line therefore is seized by the operation of relays 606 and 607 of the by-pass selector, which takes place as hereinbefore described. The conductor corresponding to conductor 363 and associated with the second toll line is grounded, and the cut-off relay corresponding to relay 103 of the circuit TLC, Fig. 1, is operated as a result.

The operator now momentarily operates her release-answer key K8. Key K8 operates the split relay 508 so as to disconnect the answering end of the link circuit L1 from the operator's headset for the time being, and it places a ground potential on release-answer conductor 342, thereby closing a shunt circuit, through contacts of the key K1, around the winding of cut-through relay 301. Relay 301 thereupon restores and opens its locking circuit at its upper armature. With cut-through relay 301 restored and with grounded start conductor 553 of the by-pass selector BPS (now grounded at contacts of test relay 607) connected to drive-answer conductor 341 at armature 544 of the operated dial-answer relay 517, the self-interrupting drive magnet 310 of the answering switch AS now operates through contacts of the talk key K1 to drive the wipers 311-315 until the driving circuit is opened upon the operation of stop relay 518. Relay 518 operates when the toll line selected by the by-pass selector BPS is reached.

It will be recalled that mark-answer conductor 345 is grounded in the position equipment at the upper contacts of the dial-answer relay 517. The grounded mark-answer conductor 345 is connected through contacts of the key K1 to the supervisory and marking wiper 314. Now, when the wipers of the answering switch AS reach the fourth set of bank contacts shown, they are connected with the second toll line in the group including the toll line TL. The now-grounded wiper 314 therefore extends ground potential over the marking conductor of the second toll line (corresponding to marking conductor 109 of the toll line TL). This conductor extends to and connects with a marking conductor (similar to the marking conductor 365) which extends to the bank of the by-pass selector. 70 The wiper 635 is now standing on the bank contact to which the marking conductor of the second toll line (corresponding to conductor 365 of the toll line TL) is connected. Ground potential, therefore, is extended through wiper 635, armature 644, conductor 556, and the lower arma-

ture of the operated dial-answer relay 517, to the operating winding of stop relay 518. Relay 518 now operates and opens the above-traced driving circuit of magnet 310 of the answering switch AS at its upper armature, leaving the wipers of the answering switch in association with the second toll line of the group including the toll line TL.

As a further result of its operation, stop relay 518 extends an energizing potential to cut 10 through conductor 342, from the resistor 539, closing a circuit through contacts of the key K1 for the cut-through relay 301. Relay 301 now reoperates and connects up the associated wipers, in addition to again locking itself at its 15 upper armature through the resistor 337 and operating magnet 310.

It will be understood, of course, that the operator is in telephonic communication with the newly selected toll line as soon as this toll line 20 has been seized by the by-pass selector BPS, and that a second talking connection to the toll line is completed from the operator's headset by way of the wipers of the answering switch AS, when this switch is positioned on the new toll line as 25 above described. The operator is informed of the final positioning of the answering switch AS and the operation of the cut-through relay 301 when the calling supervisory lamp 335 becomes lighted through contacts of the cut-through relay 301 30 because of the ground potential now supplied over conductor 345 to marking wiper 314 as above pointed out.

The operator may now restore the dial-answer key K13, whereupon relays 519, 517, and 516 restore and the by-pass selector BPS releases. When cut-off relay 516 restores, battery potential is applied by way of resistor 538 and contacts of the operated identity relay 505 to conductor 346, causing the identity lamp 333 associated with the 40 second toll line in the group in question to become lighted through wiper 313 and contacts of the operated key K1. The operator is thereby informed of the particular trunk line in the group with which he has made connection. It may 45 be pointed out that the upper winding of identity relay 505 is energized over cut-through-answer conductor in parallel with the winding of relay 301 of the link L1.

With the above mentioned restoration of dial- 50 answering relay 517, the tip-call and ring-call conductors 351 and 356 are again connected up at armatures 542 and 543 to the position talking circuit so that the two subscribers may start their conversation, even while the talking key 55 K1 is in operated position, or at any rate the called subscriber may be informed by the operator that he may now proceed with the conversation.

A similar substitution having been made by the 60 distant operator in substantially the same way, the two subscribers may converse as desired over the new toll line. The talking circuit includes only the strands of the link L1, as soon as the operator restores the key K1 and permits the 65 link-connect relay 303 to restore.

It will be understood, of course, that the trunk lines such as TL are connected up in the same order in the banks of the by-pass switches in both exchanges, so that both the by-pass switches 70 will select the same idle toll line under conditions similar to those described above.

Clearing out after conversation

When the subscribers replace their receivers 75

at the end of the conversation, disconnect supervision is given to the operator.

When the called subscriber replaces his receiver, current flow is again resumed in conductors 406 and 408 outgoing from the toll service circuit TSC, whereupon supervision-repeating relay 404 again operates and places the lower winding of switching relay 401 in shunt of the upper winding so as to again increase the current-flow over conductor 373 to cause the answering-supervisory lamp 337 to become lighted as a disconnect signal.

At about the same time, ringing current is received over the toll line from the distant exchange to operate the ring-up relay 402 to light the calling supervisory lamp 335 as a disconnect signal.

The operator now throws the key K1 to talking position (again operating link connect relay 303) to converse with the distant operator and is informed that the connection may be cleared out. To clear out the connection, the operator momentarily operates the wipe-out key K7. The key K7 places a ground potential on the release-answer conductor 342 to shunt the answering cut-through relay 301, and it places a ground potential on the release-call conductor 353 to shunt the locking winding of the calling cut-through relay 304. As a result, both of these relays restore and each opens its locking circuit and disconnects the associated wipers. The operator then restores the key K1, permitting link-connect relay 303 to restore, leaving the link L1 in normal condition.

When the cut-through relay 304 at the calling switch CS restores and disconnects the supervisory wiper 324, the circuit of switching relay 401 of the toll service circuit TSC is opened. Relay 401 therefore restores and again connects the incoming conductors 371 and 374 to the outgoing conductors 408 and 406, at the same time opening both bridges. Since there is no holding bridge across conductors 371 and 374 at this time, the connection through the toll-service train to the called line is permitted to be cleared out in the well-known manner.

A through call

The way in which a through call is handled will now be explained. By a through call is meant a call received over a toll line of one group and completed over a toll line in another group, the exchange containing the illustrated switchboard being the switching point.

It will be assumed that a call is received over a toll line in the second group, the toll line group associated with the fifth and sixth illustrated contact sets in the banks of the calling and answering switches of the link L1. It will be assumed further that the answering switch AS of the link L1 is the one to respond to the call and connect with the calling toll line in the hereinbefore described manner. It will be recalled that the key K1 is thrown to talking position at this time by the operator; that the link-connect relay 303 is operated; and that the cut-through relay 304 responds when the calling line is reached and the step relay 506 in the position circuit has become energized. Identity lamp 334 is lighted 70 through wiper 313 and over lamp conductor 346 to identify the calling group.

It will be assumed that the calling operator informs the answering operator that the call is to be completed over the toll line group including the toll line TL, Fig. 1. That being the case, the

answering operator throws the dial-toll key K15 with results hereinbefore described, thereby preparing the by-pass selector BPS, Fig. 6, for operation. The by-pass selector BPS responds to the manipulation of the calling device CD in accordance with the number 11, bringing its wipers opposite the first level of bank contacts and rotating them over the contacts assigned to the desired toll line group. It will be assumed that the toll line TL is the one selected, in which case 10 connection is made thereto by the by-pass selector and the calling switch CS is caused to connect with this toll line in the manner hereinbefore described, and the cut-through relay 304 in the link circuit L1 is operated. 15

The tandem operator now throws her ringing key K11 and signals the operator in the exchange to which the toll line TL extends.

As soon as the distant operator responds, the switching operator restores the key K1 of the link L1 and permits the calling and terminating operators to converse with each other pursuant to the final setting up of the desired connection, and she takes no further notice of the established connection except as she is signaled by her ring-up relay 302 to do so.

When the through connection is to be released, one or the other of the originating and terminating operators projects ringing current over the established connection, operating the ring-up relay 302 to lock itself under the control of the key K1 to light the supervisory lamp 335.

The operator responds to the lighted supervisory lamp 335 by throwing her key K1 to bring about the operation of link-connect relay 303, 35 and thereby place her in communication with whichever operator is telephonically connected to the established connection. If required to do so, the tandem operator may throw her ringing key to signal the other operator, which operation is ordinarily necessary only in the event that the toll lines are of such length that ringing current received over one line is so greatly attenuated that it does not pass over the other line with sufficient strength to operate the ring-up relay or other signal in the third exchange. 45

To clear out the through connection, the operator throws her wipe-out key K7 momentarily, causing relays 301 and 304 to be shunted and thereby restored in the manner pointed out hereinbefore, following which the operator restores her key K1 and the connection is cleared out. 50

Completing a delayed call

The way in which a delayed call is completed 55 will now be pointed out. It may be explained that a delayed call is a call that, for any reason, cannot be completed within given time after it is originated. In this event the calling subscriber is requested to replace his receiver and wait until he is recalled. The connection initially established between the calling line and the toll board is thereupon broken. It may conveniently be assumed that the delayed call is for a subscriber that may be reached by way of the toll line TL. 65

When the operator is ready to make another attempt to set up the connection, she may take an idle link circuit, the link circuit L1, for example, for use by throwing the talking key K1 thereof, and she precludes an appropriation of the answering switch of the link by an incoming call, by throwing any one of her dial-keys K16, K15, and K13, as in each case the cut-off relay 516 is operated through one of the relays 70 75

515, 517, and 519. It may be assumed that the dial-automatic key K16 is the one now operated, as the operator will ordinarily wish to call the local subscriber first to make sure that he is still 5 in readiness before she takes a toll line for use to try to complete the delayed call.

When the dial-automatic key K16 is operated to associate the calling device CD with the talking circuit, start relay 515 and cut-off relay 516 10 are operated as before described. Relay 516 prevents ground potential on finder-start conductor 212 from affecting start relay 507, and start relay 515 at its upper contacts extends ground potential to the drive-call conductor 354 to start 15 the calling switch CS into operation, while at its lower armature it places a ground potential, through the lower winding of stop relay 518, on the group-mark conductor 358 so as to cause the calling switch CS to stop on an idle toll-service 20 circuit, such as the toll service circuit TSC. The operations have been described in detail herein-before.

After the toll service circuit TSC has been seized the operator operates her calling device 25 CD and causes a connection to be set up through circuit TSC to the called line. She signals the subscriber on the called line by means of her ring-call key K11 and requests the subscriber to wait while she makes a further attempt 30 to complete the connection.

The operator now throws the dial-answer key K13 and restores the dial-automatic key K16, whereupon start relay 515 restores, but cut-off relay 516 is maintained operated in series with dial-answer relay 517 and selector seizing relay 519, both of which relays are operated through contacts of the dial answer key K13 to prepare the by-pass selector BPS for operation and to 40 prepare the answering switch AS to operate to find the position taken by the by-pass selector BPS.

The operator now turns the calling device in accordance with the number assigned to the toll line group including the toll line TL, whereupon 45 the by-pass selector BPS operates in the hereinbefore described manner to search over the group of toll lines. It will be assumed that the toll line TL is idle and that it is therefore taken for use by the by-pass selector BPS.

As has been hereinbefore described, with dial-answer relay 517 operated in addition to selector-seizing relay 519, the grounding of start conductor 553 of the by-pass selector (when the by-pass selector finds an idle toll line), results in 55 an extension of ground potential to drive-answer conductor 341 to operate the driving magnet 310 of the answering switch AS through contacts of the key K1. The answering switch AS operates until it makes connection with the selected toll line TL, whereupon the stop relay 518 is operated to open the driving circuit and to close a circuit to the cut-through-answer conductor 355 to operate the cut-through relay 301. The stopping circuit for relay 518 at this time 60 includes the mark-answer conductor 345, grounded at the upper contacts of the dial-answer relay 517, marking wiper 314, conductors 109 and 365, wiper 635 of the by-pass selector, mark-answer conductor 556, and contacts of the 65 operated dial-answer relay 517.

The connection between the calling line and the toll line TL has now been completed through the link L1.

The operator may now throw the ring-answer, toll, key to signal the operator in the exchange 75

to which the toll line TL extends and solicit her aid in completing the delayed call.

The established connection is cleared out in the manner described hereinbefore, either by successive operations of keys K13 and K8 to release the two ends of the link L1 successively, or by an operation of wipe-out key K7 to release both ends simultaneously.

Using the local switch train

As is well understood, a so-called toll-service train of switches is preferably provided through which toll operators may set up connections to called lines, while local connections between subscribers of the same exchange are set up through what is known as a local switch train. Some operating telephone companies do not go to the expense of installing a train of toll service switches, but provide the toll operators with facilities for using the regular local switch train in completing connections to called lines.

In the event that the toll board disclosed herein is installed in an exchange wherein the toll calls are to be completed through the local switch train to local lines, the toll service circuit TSC, Fig. 4, is replaced by the local circuit LC, Fig. 7. The incoming conductors 371—374, Fig. 3, then connect with conductors 371'—374', Fig. 7. The outgoing conductors 406' and 408' in Fig. 7 extend to a local first selector, whose contact banks 30 may be multiplied with the banks of the local selectors used by calling subscribers.

When the local circuit LC is seized, by switch AS, for example, the test circuit for the seizing switch over conductor 372' includes contacts of 35 switching relay 701 and resistor 705. Switching relay 701 is operated over supervisory conductor 373' and through its high-resistance upper winding to open the direct connection between the incoming and outgoing talking conductors and to 40 bridge the left-hand and right-hand windings of the repeating coil 702 across the incoming and outgoing conductors, respectively. The line relay (not shown) of the local selector to which outgoing conductors 406' and 408' extend is now energized through the right-hand repeating-coil windings, the upper winding of the electro-polarized supervisory relay 703, and resistor 704. The polarizing winding of relay 703 is now energized in a circuit from the grounded release-trunk conductor 372' through contacts of relay 701 and resistor 709. As indicated by the direction of the arrows associated with the windings of supervisory relay 703, the current flow in either winding of the relay agrees with the direction of current flow 55 in the other winding so that the relay is now operated to shunt the low-resistance lower winding of switching relay 701 around its high resistance upper winding, so as to give a lighted condition of the supervisory lamp 337 of the calling 60 switch CS.

The operator now manipulates her calling device to dial the desired number. Each time the current flow over the incoming supervisory conductor 373' is discontinued responsive to the off-normal movement of the calling device CD, Fig. 5, switching relay 701 is restored to unbridge and by-pass the windings of repeating coil 702 and connect incoming conductors 371' and 374' directly to outgoing conductors 406' and 408' to 70 enable the dial impulse to pass directly through the circuit LC, as described in connection with the toll service circuit TSC, Fig. 4.

Each time the calling device again returns to its normal position, current-flow over supervisory 75

conductor 373' is resumed and switching relay 701 reoperates, following which the electro-polarized supervisory relay 703 (having restored) reoperates.

5 After the connection has been extended to the desired line and the called subscriber has responded, current-flow in conductors 406' and 408' is reversed in the well-known manner by the final selector, or connector, whereupon electro-polarized supervisory relay 703 restores and disconnects the lower winding of switching relay 701, thereby reducing the current flow over supervisory conductors 373' so as to result in the answering supervisory lamp 337 of link L1 becoming extinguished to give answering supervision.

Additional description of the by-pass selector

20 The by-pass selector BPS, Fig. 6, has certain desirable features which have not been adequately pointed out in the foregoing description. Such features will now be explained.

25 As pointed out hereinbefore, the by-pass selector BPS operates normally as a two-digit selector; that is, it responds to the first digit received to raise its wipers opposite a desired level of bank contacts, and it responds to the second digit to rotate the wipers over the contacts in the selected level to bring them into engagement 30 with the first set of contacts assigned to a desired group of toll lines. Now, when a toll line group contains eight or ten toll lines and the traffic directed to this group, is, therefore, relatively heavy, a single digit may be advantageously 35 employed to index this toll line group, thereby saving the time that would otherwise be employed in dialing a second digit. It is assumed that the second level of bank contacts of the by-pass selector BPS is allotted to a single large group instead of to two or more small groups of toll lines. That being the case, it is certain that this group is the one wanted whenever the wipers of the by-pass selector are brought to rest opposite the second level of bank contacts. Therefore, 40 the second level contacts 613 are arranged to be closed whenever the wipers are opposite the second level.

45 It will be recalled that release, vertical-series, and cut-in relays 602, 603, and 604 are energized continuously while the line relay 601 if vibrating its contacts to operate the vertical magnet 615 pursuant to the execution of the vertical movement of the by-pass selector, and that vertical-series relay 615 restored at the end of the vertical movement, but cut-in relay 604 remains operated 50 in a locking circuit which includes the grounded holding conductor 554 and contacts of rotary series relay 605, as well as its own upper armature. Therefore, when the wipers 631—635 come to rest 55 opposite the second level of bank contacts, and vertical series relay 603 restores, an automatic cut-in circuit for rotary magnet 616 by way of rotary-series relay 605 is closed at the lower contacts of vertical-series relay 603, which circuit 60 includes shaft contacts 613 and the lower contacts of the operated cut-in relay 604.

65 Magnet 616 operates in this circuit to drive the wipers 631—635 onto the first set of bank contacts in the second level, and rotary series relay 605 operates to break the above-mentioned locking circuit for relay 604 at its upper armature, so as to restore the cut-in relay to start the regular hunting action of the selector.

70 In order to insure that cut-in relay 604 is maintained operated in this instance long enough to

75 permit rotary magnet 616 to complete its step and not be prematurely restored responsive to the opening of its locking circuit at the upper contacts of rotary series relay 605, the closing of the above-mentioned cut-in circuit for rotary magnet 616 results in the closure of a new locking circuit for cut-in relay 604 in parallel with rotary magnet 616 and through the interrupter contacts of the rotary magnet. This circuit includes the operated inner lower armature of relay 604, resistor 608, and the operated upper armature of relay 604. This auxiliary locking circuit remains closed until the rotary magnet 616 has operated sufficiently to separate its interrupter contacts, at which time the wipers 631 will have been advanced into engagement with the first set of bank contacts in the selected level. Because of the current-limiting effect of resistor 608, the current flow in the second locking circuit is very small and the relay 604 quickly restores responsive to the opening of the interrupter contacts of magnet 616. Upon restoring, relay 604 opens the cut-in circuit at its lower contact, whereupon magnet 616 restores and again closes its interrupter contacts, but relay 604 does not reoperate 25 as it has opened its locking circuit. Resistor 608 prevents a premature operation of the magnet 616 in parallel with the initial locking circuit of relay 604.

30 A moment later, the slow-acting rotary series relay 605 falls back and initiates the regular hunting movement of the selector hereinbefore described.

35 If it is desired that the operator be able to connect with a specific toll line of the group connected to the second level of contacts, the toll lines in this group may be multiplied to another level of the selector for this purpose. It will be understood, of course, that, as to each level except the second, the operator may operate the 40 by-pass selector to bring the wipers thereof onto any desired idle toll line in a group, instead of causing the wipers to come to rest on the first toll line of a group, at the end of a second digit assigned thereto. This feature is of utility if the 45 operator is working in conjunction with an operator at a distant manual toll board and it becomes necessary for a new toll line of the group to be substituted for one that has been found to be defective. To make this substitution, the operator merely asks the operator at the distant manual board the number of the new toll line which she desires to use in place of the defective one and then proceeds to cause the by-pass selector BPS to make connection with the specific 50 new idle toll line named by the distant manual operator.

Segregating the positions of the toll board

55 The toll board shown and herein described is, as stated, one with combination positions. Now, if it is desired to use a toll board such as is disclosed herein for segregated service, one or more positions may be assigned to the handling of calls originated by local subscribers; one or more positions may be assigned to the handling of calls incoming over toll lines; and one or more positions may be assigned to the handling of delayed calls. With this arrangement, the toll service trunks may be omitted from the banks of the 70 calling switches of the links at the positions which handle only calls originated by local subscribers, and the trunks incoming from local selector banks to long distance circuits (such as the circuit LD, Fig. 2,) may be omitted from the answering 75

switches of the links at the positions assigned to handle only calls incoming over toll lines, while the positions at which delayed calls only are completed may be equipped in like manner.

5 Having described the invention, what is considered to be new and is desired to be protected by Letters Patent, will be set forth in the following claims.

What is claimed is:

- 10 1. In a toll board for use in an automatic exchange, a group of link circuits at an operator's position, one end of each link circuit terminating in an answering switch and the other end in a calling switch, toll lines accessible both to the answering switches and to the calling switches, incoming local circuits accessible to the answering switches, outgoing local circuits accessible to the calling switches, means for operating the answering switch of any link as a finder to find any 15 calling incoming local circuit or any calling toll line accessible to the answering switch, means under the control of the operator in such position for operating the calling switch of the same link circuit to extend the incoming connection 20 to a toll line accessible to the calling switch, and means also under the control of the operator at said position effective when the answered call is from a toll line for operating the calling switch of the link to make connection with an idle local 25 outgoing circuit.
- 20 2. In a toll board for use in an automatic exchange, toll lines extending between said automatic exchange and another exchange, toll service trunks extending from the toll board to automatic switching apparatus through which connections can be set up to the lines of local subscribers, an operator's link at said toll board, an answering switch terminating one end of said link and having access to said toll lines, a calling 30 switch terminating the other end of said link and having access to said toll service trunks, and means under the control of the operator for completing calls incoming over said toll line through said answering switch and said calling switch of the link by way of said toll service trunks.
- 30 3. In a toll board for use in an automatic exchange, an operator's link, an answering switch terminating one end of said link and a calling switch terminating the other end, two groups of toll lines accessible to both of said switches, a group of toll service trunks accessible to the calling switch through which connections may be set up by way of the automatic-exchange equipment to local lines, and means whereby an operator may control the establishment of connections through the answering and calling switches of said link, whereby a call incoming over either group of toll lines may be completed through an 35 answering and a calling switch to the other group of toll lines and whereby a call incoming over a toll line in either group may be completed through an answering and a calling switch to any one of the local trunk lines.
- 40 4. In a toll board for use in an automatic exchange, an operator's link, an answering switch terminating one end of said link and a calling switch terminating the other end, long-distance circuits incoming from the local automatic switches to the control board and accessible to 45 said answering switch, toll lines outgoing from said toll board to a distant exchange and accessible to said calling switch, and means operable under the control of an operator for establishing connections between said incoming long distance

trunk and said toll line by way of said answering and calling switches and said link.

5 5. In a telephone system, an operator's link circuit, an answering switch terminating one end of said link circuit and the calling switch terminating the other end, incoming circuits accessible to said answering switch, two groups of said outgoing circuits accessible to said calling switch, means effective when there is a call on any one of said incoming circuits for operating 10 said answering switch to find and connect with the calling circuit, and means controlled by an operator for operating the calling switch of said link to make connection with an idle circuit in either desired one of said outgoing groups, whereby the 15 call on the incoming circuit is extended through said link circuit by way of the answering and calling switches to an idle outgoing circuit in the desired group.

6 6. In a telephone system, an operator's link, 20 an answering switch terminating one end of said link and a calling switch terminating the other end, two groups of two-way telephone circuits accessible to said answering switch and to said calling switch, means effective when there is an 25 incoming call on a line in either group for causing said answering switch to hunt for and connect with the calling circuit, and means controlled by an operator for operating said calling switch to extend a connection to an idle circuit 30 in the other group.

7 7. In a telephone system, an operator's link, an answering switch terminating one end of said link and a calling switch terminating the other end, incoming circuits accessible to said answering switch, groups of outgoing circuits accessible to said calling switch, a by-pass selector also having access to said groups of calling circuits, means for operating said answering switch to make connection with any one of said incoming 40 circuits on which there is a call waiting, means for operating the by-pass selector to select an idle circuit in the group through which it is desired to extend the incoming call, and means for then operating the calling switch of the link 45 to hunt for and connect with the idle line selected by the by-pass selector.

8 8. In a telephone system, an operator's link, an answering switch terminating the answering end of said link and a calling switch terminating 50 the calling end of said link, incoming circuits accessible to said answering switch, outgoing circuits accessible to said calling switch, means for operating said answering switch to find and make connection with any one of said incoming 55 circuits on which there is a call waiting, a by-pass selector having access to the said outgoing circuits, means controlled by an operator for operating said by-pass selector to make connection with the one of said outgoing circuits over 60 which it is desired to extend the incoming call, and means for causing said calling switch to operate automatically to find and connect with the outgoing circuit to which connection has been made by the by-pass selector, whereby any 65 calling incoming circuit may be connected through the answering switch, the operator's link, and the calling switch to the desired outgoing circuit.

9 9. In a telephone system an operator's link a 70 first switch terminating one end of said link and a second switch terminating the other end of said link telephone circuits accessible to the first switch other telephone circuits accessible to the second switch a by-pass selector having ac- 75

cess to all of said circuits means under the control of an operator for operating said by-pass switch to make connection with one of the circuits in the first group, means for causing the 5 first link switch to operate to find and connect the link with the circuit in the first group with which connection has been made by the by-pass selector, means also under the control of said operator for operating said by-pass selector to 10 make connection with a circuit in the second group, and means for operating the second link switch to find the circuit in the second group with which connection has been made by the by-pass selector and to connect the link circuit therewith, whereby the found circuit in the first 15 group is connected through said link circuit to the found circuit in the second group.

10. In a telephone system, a group of operator's link circuits, a separate group of incoming 20 trunk circuits through which connections are to be extended by way of said link circuits, means responsive to a call being received on any one of said incoming trunk circuits for automatically making a connection between the incoming circuit and an idle one of said link circuits, a group of identity lamps, and means for lighting any one of said lamps, depending upon the trunk group over which the incoming call is received, for indicating to the operator the group to which the connected calling circuit 25 belongs.

11. In a telephone system, an operator's switchboard, call-receiving circuits associated with said switchboard and divided into groups, a 30 switch associated with said operator's switchboard and having access to all of said circuits, means for variably positioning said switch to make connection with any one of said circuits on which a call is waiting, and means controlled 35 according to the assumed position of said switch and including a separate identity lamp common to the call receiving circuits of each group for indicating to the operator at said switchboard the group to which a circuit belongs that has been 40 connected with by said switch.

12. In a telephone system, an operator's switchboard, link circuits at said switchboard through which incoming calls may be extended, 45 circuits associated with said switchboard over which incoming calls are received, automatic switching apparatus interposed between the incoming circuits and said links for making a connection between an incoming circuit on which a call is waiting and an idle link, a separate 50 manual key assigned to each link, and means depending upon the manual key of an idle link having been manipulated by the operator for permitting said automatic switching mechanism to direct an incoming call to such link.

60. 13. In a telephone system, an operator's switchboard, call-forwarding links at said switchboard, circuits associated with said switchboard over which calls are received, a finder switch terminating each link and having access to the incoming 65 circuits, a separate talking key for each of said link circuits, and means depending upon an operation of the talking key of an idle link by the operator for enabling the finder switch terminating said link circuit to find and connect said link circuit with an incoming circuit on which a call is 70 waiting.

14. In a telephone system, an operator's switchboard, call-forwarding links at said switchboard, incoming circuits associated with said switchboard over which calls may be received, a finder 75

switch terminating each link and having access to the incoming circuits, a separate talking key for each of said link circuits, means depending upon an operation of the talking key of an idle link circuit by the operator for enabling the finder switch terminating said link circuit to find and connect said link circuit with an incoming circuit on which a call is waiting, and additional means common to all of the said link circuits and operable under the control of said operator for preventing the finder associated with an idle link on which the talking key has been operated from responding to a waiting call. 5

15. In a telephone system, an operator's switchboard, call-extending links at said switchboard, incoming circuits over which calls may be received at said switchboard, outgoing circuits over which calls may be extended from said switchboard, automatic switching equipment operable when an incoming call is received for interconnecting the circuit over which the incoming call is received with an idle link circuit, automatic switching apparatus operable under the control of the operator for further extending the concerned connection by way of the link circuit in 25 use to a desired outgoing circuit, and means under the control of the operator for selectively releasing either the automatic switching apparatus over which the incoming call is received or the automatic switching apparatus over which the call is 30 extended. 15

16. In a telephone system, an operator's switchboard, call-extending links thereat, a separate calling switch terminating each of said links and through which incoming calls may be further 35 extended, groups of outgoing circuits associated with such switchboard and accessible to said calling switches, a by-pass selector at said switchboard having access to all of said outgoing circuits, means for operating the by-pass selector to 40 select an idle circuit in any desired group, means effective thereafter for causing the calling switch of a link on which an incoming call is waiting to find and connect with the same outgoing circuit selected by the by-pass selector, another group of 45 outgoing circuits accessible to the calling switches, and means under the control of the operator at said switchboard for causing the calling switch of any desired link circuit to hunt for and connect with any idle circuit in the last named group exclusive of an operation of said by-pass selector. 50

17. In a telephone system, an operator's switchboard, a group of incoming circuits associated with said operator's switchboard and over which incoming calls may be received, means including 55 automatic switching apparatus associated with said switchboard for further extending any one of said circuits over which an incoming call has been received at said operator's switchboard, each of said incoming circuits being divided into two 60 serially related disconnected sections telephonically interconnected, means at the operator's switchboard for projecting ringing current back over any incoming circuit, and means at the circuit concerned thereupon effective to join the two 65 sections together electrically so as to permit the ringing current to pass over both sections in series.

18. In a telephone toll system, two exchanges interconnected by toll lines, two toll operators' 70 hunting switches located in said exchanges, respectively, and both having access to said toll lines in the same order of succession, and means under the control of toll operators and effective when connection with the same toll line in each ex- 75

- change is desired, for operating both switches to search over said toll lines and to make connection with the first idle one, whereby an inter-exchange connection may be set up through said switches 5 and an idle toll line responsive to the same act performed by an operator in each exchange.
19. In a telephone toll system, two exchanges interconnected by toll lines and each including an automatic toll board presided over by an operator 10 and capable of control by the operator pursuant to the setting up of a toll-line connection with lines of local subscribers, whereby a subscriber's line in one exchange may be interconnected with a subscriber's line in the other 15 exchange by way of a toll line and both toll boards, and means under the control of the operators at the toll boards and effective when it is desired to substitute a new toll line for one included in a subscriber-to-subscriber connection for transferring each subscriber's line to the same alternative toll line by repositioning the automatic toll board switching apparatus in each exchange.
20. In a telephone toll system, local lines, a group of toll lines, automatic switching apparatus

controlled by a toll operator for effecting interconnection between toll lines and local lines, means controlled by the toll operator for operating said apparatus when desired to search over the toll-line group and make connection with the first idle one, and means controlled by the toll operator for operating said apparatus when desired to pass over any desired portion of the toll line group to make connection with a specific, predetermined toll line of the group. 5

21. In a telephone system, a group of operator's link circuits, separate groups of incoming circuits from which connections are to be extended by way of said link circuits, means responsive to a call on any one of said incoming circuits for making a connection between such incoming circuit and one of said link circuits, a separate identity lamp assigned to each group of incoming circuits, and means effective upon said connection being made and independent of which of said link circuits is involved for lighting the one of said identity lamps which is assigned to the group to which the connected calling line belongs. 10 15 20
